[57] CLAIM

The ornamental design for a spinning suction toy, as
shown and described.

DESCRIPTION

FIG. 1 is a front elevational view of a spinning suction toy showing my new design, the side opposite being substantially a mirror image;

FIG. 2 is a top plan view thereof;

FIG. 3 is a side elevational view thereof, the side opposite being substantially a mirror image; and,

FIG. 4 is a top plan view of the sliding elements shown
in FIGS. 1 through 3.

FIG 1

FIG 3

FIG 2

FIG 4
